(Cl. D44—1)

To all whom it may concern:

Be it known, that I, Wilbur H. Lynn, a citizen of the United States, residing at Chippewa Township, Beaver County, Pennsylvania, have invented a new, original, and ornamental Design for an Ingredient Retainer or the like, of which the following is a specification, reference being had to the accompanying drawing, forming a part hereof.

Figure 1 is a perspective view of an ingredient retainer or the like, showing my new design;

The tumbler is shown in broken lines for purposes of illustration.

I claim:

The ornamental design for an ingredient retainer or the like, as shown and described.
